[57] CLAIM

The ornamental design for a roof panel for a modular storage container, as shown and described.

DESCRIPTION

FIG. 1 is a perspective view of a roof panel for a modular storage container showing my new design;

FIG. 2 is a right side elevational view thereof;

FIG. 3 is a front elevational view thereof;

FIG. 4 is a bottom plan view thereof;

FIG. 5 is a top plan view thereof; and,

FIG. 6 is a rear elevational view thereof.
